UNITED STATES PATENT OFFICE.

FRED SEVER AND MAGNUS JOHNSON, OF LATOUCHE, TERRITORY OF ALASKA.

CLOTHES CLEANER.

Application filed February 11, 1925. Serial No. 8,496.

This invention relates to clothes cleaners and contemplates a provision of electrically operated means whereby the device may be run evenly and smoothly over the clothes in order to cleanse the same.

Another object of the invention is the provision of a member which rotates therein in order to remove dirt or soil from the clothing and is easily brought into contact with the clothing.

With the above and other objects in view, the invention further includes the following novel features and details of construction to be hereinafter more fully described, illustrated in the accompanying drawings and pointed out in the appended claim.

In the drawings:

Figure 1 is a side elevation of the present invention showing the same applied to an electrically operated means.

Figure 2 is a transverse section taken through the device and showing the mountings of the brush member and dust conveying means.

Figure 3 is a diagrammatic plan view of the invention per se, showing the various chambers and elements of construction contained therein.

Referring to the drawings in detail, where in like characters of reference denote corresponding parts, the reference character 10 indicates the electrically operated means which may be in the form of an electric motor which carries therein a rotatable shaft 11 which is connected with the mechanism of the device for the operation of the same.

In the present invention, and in order to clearly illustrate the cardinal purposes and advantages of the above entitled invention, and referring especially to Figure 3 of the drawing, the reference character 12 indicates the housing within which the elements above referred to are enclosed. A brush head 13 having brush bristles 14 extending from the outer sides thereof has extending exteriorly and centrally therefrom a shaft 15 which is mounted within bearings 16 within the housing 12 and as clearly illustrated in Figure 2 of the drawing, the brush bristles 14 of the brush head 13 extend through the opening of the housing 12 whereby the same may come in contact with the clothing to be cleaned. One end of the shaft 15 extends through the bearing member 16 and carries upon the outer end portion thereof a gear 17, the purpose of which will be presently

apparent. Mounted within this housing 12 is a similar shaft 18 which is carried in bearings at opposite ends of the housing 12 and which carries a gear 19 upon the outer end portion thereof which is adapted to mesh with or engage the gear 17 by two idler gears 20 and 21 respectively.

The outer end portion of the shaft 18 is connected with a source of power such as an electric motor and will rotate the brush member 13 and shaft 18. Pairs of fan members 22 are supported upon transversely extending shafts 23 which are connected to the shaft 18 and these fan members being secured upon opposite end portions of the shaft 18 within the housing 12 and are enclosed within housing member 24 having restricted openings 25 around the shaft 18 whereby the same may freely rotate therein and completely house the fan members 22 therein. A partition wall 26 extends vertically within the housing 12 at the inner end portion of the housing members 24. This partition member 26 defines a chamber 27 which is adapted to receive or hold dust or the like and the top of the same is closed by a dust proof screen. The inner end portions of the housing 12 are cut away as at 28 in order to communicate with the compartment 27 and have extending from the upper portions thereof baffle plates 29 which are downwardly inclined so as to convey the dust or dirt downwardly within the compartment 27. This compartment 27 includes a hinged door 30 whereby all of the dust contained therein may be easily and quickly removed therefrom. The gears 17, 19, 20 and 21 are also closed by a separable housing member 31 which is secured to the housing 12 through the instrumentality of suitable fastening elements 32.

In the use and operation of the present invention it is clearly apparent that the device may be laid upon a piece of clothing and after the motor 10 or electrically operated means rotates the mechanism within the housing 12, namely, the brush head 13 and the shaft 18 which carries thereon the fan members 22, it is clearly apparent that the brush member 13 when rotated in the direction of the arrow as clearly illustrated in Figure 2 of the drawings, the dust will be conveyed into the chamber in which the shaft 18 rotates and thrown against the wall or partition 26 and owing to the mounting of the fan members 22 upon the outer end

2
portions of the shaft 18 a suction or vacuum will be created in the compartments 24 which houses the same whereby the dust or dirt removed from the clothing will be conveyed therein and upon the successive revolutions of the fan members 22 the said dirt or dust will be conveyed through the broken away portions 25 of the housing 24 and deflected downwardly through the medium of the baffle plates 29 into the compartment 27 from whence it may be removed through the opening of the door 30. It is also apparent that the air may travel from the brush head member 13 into the compartment in which the shaft 18 rotates into the housing 24 past the baffle plates 29 and through a dust proof screen 33 secured to the housing and directly above the compartment 27 whereby a complete circulation of air is assured in order to create a suitable suction in order to convey the dirt or dust into the compartment 27.

The invention is susceptible of various changes in its form, proportions and minor details of construction, and the right is herein reserved to make such changes as properly fall within the scope of the appended claim.

Having described the invention what is claimed is:—

In a clothes cleaner, a casing, a rotatable shaft mounted in bearings on opposite sides of the casing a cylindrical brush carried by the shaft, the said brush at its lower portion projecting through an opening at one end of the casing, a second rotatable shaft arranged parallel to the other shaft and also arranged to rotate simultaneously with the said other shaft, a fan at each end of the second shaft, a partition having enlarged holes for the second shaft, said partition partially inclosing the fans, thereby forming a fan chamber at each side of the casing and also forming with the casing a narrow compartment at the end farthest from the brush, the parts surrounding the fans having openings leading into the narrow compartment, baffle plates extending above the last mentioned openings and projecting into said compartment whereby air is drawn through the enlarged holes around the second shaft into the fan chambers and exhausted into the narrow compartment, and a screen covering an opening in the casing communicating with the narrow compartment.

In testimony whereof we affix our signatures.

FRED SEVER.
MAGNUS JOHNSON.
